UNITED STATES PATENT OFFICE.

FRANK J. BORRES, OF PITTSBURGH, PENNSYLVANIA.

SNOW-REMOVER.

1,211,280.

Specification of Letters Patent. Patented Jan. 2, 1917.

Application filed June 9, 1916. Serial No. 102,750.

To all whom it may concern:

Be it known that I, FRANK J. BORRES, a citizen of the United States, residing at Pittsburgh, in the county of Allegheny and 5 State of Pennsylvania, have invented new and useful Improvements in Snow-Removers, of which the following is a specification.

The invention relates to an improved apparatus 10 designed particularly for removing snow from railway tracks and loading the same onto cars for removal.

The invention is directed to a means whereby the snow cutter and lifter is 15 adapted for travel on a railway track under steam or other propulsion and is operative to cut a channel through the snow and to pick up the material and carry the same rearwardly. With the snow removing car 20 there is associated a series of any number of additional cars which are constructed to take the material picked up by the snow remover, and carry it rearwardly to the rear-most or other selected car of the train, into 25 which it is delivered. The constructing features involves means whereby the carriers on each car are operated through the movement of the car, with the operating means arranged for manual control so that it may be 30 cut out at will. By this means as soon as a particular car is filled it is cut out from the loading operation and the next car in advance filled and so on until the train is loaded.

The invention in the preferred form of 35 details will be described in the following specification, reference being had particularly to the accompanying drawings, in which:

Figure 1 is a view in side elevation of the improved snow remover; Fig. 2 is a 40 plan of the same; Fig. 3 is a front elevation of the same; Fig. 4 is a side elevation of a train made up of a series of cars; Fig. 45 5 is a front elevation of one of the loading cars; Fig. 6 is a view in elevation partly in section of the same. Fig. 7 is a section on line 7—7 of Fig. 6.

The invention contemplates the provision 50 of a snow remover and the coupling therewith of a series of cars especially adapted to receive the material from such snow re-

mover with the entire construction arranged so that the cars may be successfully loaded from the rear and to the front end of the train. The independent structure of the loading cars permits the train to be made up of any number of such cars without any change whatever.

The snow remover provides a structure, which is adapted to cut its way through a snow bank and pick up all of the material included between such limits, transporting 65 such material to the rear of the snow remover for delivery to the loading cars.

The snow remover comprises a platform 1, upon the usual wheel structure 2, so that the remover as a whole is adapted for 70 travel upon the usual railway tracks. The platform is provided with metal sides 4 from a box like structure without ends, and at the forward end of the sides and platform are arranged shields 5 in the form of 75 rectangular metallic sections, preferably steel and suitably braced and supported from the body. The shields 5, which are in effect, cutters, extend from the upper edge of the side walls to a point immediately 80 above the ties, being arranged in advance of the body and preferably inclined outwardly to a slight degree so that in the forward movement of the remover, the shields, one on each side, will cut their way into 85 a bank of snow to separate a portion thereof of greater width than the similar dimensions of the track and by such separation, loosen the intermediate portion to a greater or less extent. Mounted in the 90 framework of the body at the forward end is a transverse axle 6, on which is arranged a drum 7 and mounted in the rear portion of the body at a point above the side walls thereof, is an axle 8, carrying a comparatively small drum 9. The drums are practically of the full width of the body and a belt 10 is adapted for travel, about the drums, said belt bearing upon its surface a series of buckets or other elevators 11. 100 The disposition of the parts is such that the buckets at their extreme forward and lower limit of movement are positioned close to the ties, so that as they advance upwardly they will take up at said part all material 105 or snow and carry the same rearwardly.

The belt 10 is preferably driven from a motor 12 of any appropriate type, supported upon a superstructure or elevated platform 13 mounted on the body, appropriate controls, not shown, being provided for the motor, and access to the platform 13 is had through a ladder or the like 14.

With the remover I contemplate the use of any desired number of what I call loading cars, adapted and constructed to receive the material from the loader in order that the same may be transported to any suitable dump. The loading cars are identical, one with another, and a detailed description of one will suffice for all. The loading car comprises a platform 15, having the usual trucks and wheels whereby it is adapted for travel on the track 3 to form part of the train, the platform being provided with side walls 17 to an appropriate height to constitute a receptacle for the material. The rear end of the space between the side walls is closed by the rear wall 18, and the forward end is provided with a hopper like construction including a forward wall 19 which curves upwardly and forwardly from the platform 15, the wall 19 being connected by side walls 20 with the side walls 17 of the car. Front and rear axle shafts 21 and 22, are mounted in uprights 23 rising from the platform, the rear shaft 22 being elevated with respect to the forward shaft. Drums 24 and 25 are mounted upon respective shafts and support a belt 26 carrying buckets or other carrying means 27. The forward or pick up end of the belt is so positioned that the buckets in their upward movement work in the hopper at the forward end of the car. The belt of the loading car is adapted to be driven at will through the forward axle of the track wheels. One of the track wheels being for this purpose provided with a gear 28 adapted to mesh with a gear 29, supported upon the shaft 30, arranged for limited horizontal movement, the shaft being connected through a rod 31 and lever 32, with an auxiliary shaft 33 supported on the platform in rear of the driving axle shaft. The shaft 33 is operated at will through the medium of meshing gears 34, and 35, the former carried on the shaft 33, and the latter upon the lower end of a control shaft 36. The control shaft extends vertically of the loading car, being mounted in suitable bearings and terminates above an elevating platform 37 supported on the uprights 23 above the belt 26. The upper end of the shaft is provided with a hand wheel or other operating means 38, whereby the shaft may be rotated.

In the particular operation of the device it will be apparent that by turning the shaft 36 to engage the gear 29 it may be thrown into or out of meshing coöperation with the gear 28, and hence the shaft 30 may be

driven or permitted to remain stationary at will. The shaft 30 carries a sprocket 39 connected by a chain 40, with a sprocket 41, upon the forward belt shaft 21, whereby it will be obvious that the belt of a particular loading car may be driven or permitted to remain stationary at will.

The platform 15 of each loading car is preferably formed of dumping openings 42 closed by doors 43 provided with suitable locks and means for controlling them so that the load of a particular car may be discharged at will.

With the parts arranged as described and a train made up of an advanced snow remover and a series of loading cars coupled successively thereto, with a propelling means as an engine or the like at the rear of the train, it will be apparent that as the train advances the snow will be cut initially by the shields, taken up by the buckets 11 of the belt 10, and carried rearwardly and discharged into the hopper of the first loading car. Assuming the belts of all loading cars in action, the belt of each loading car in succession will pick up the material from its hopper and carry it rearward to the next loading car. The final loading car of the series will have its belt stationary, by disconnection of its driving means, and the material discharged therein will be permitted to fill the box body of the car until the same is loaded. The belt of the next succeeding car is then cut out and such car loaded, the operation continuing until all of the cars of the train have been loaded when the train is removed to a dumping place and the material from the cars discharged there through the openings described.

The improvement provides a simple means for removing heavy and deep snow from the right of way in a simple and effective manner, the only requirement being the provision of an appropriate number of cars and means for driving the cars through the material to be removed.

What is claimed is:

1. A snow remover including a track traveling structure, a belt mounted thereon, elevating and carrying means arranged on the belt, a loading car in rear of the track traveling structures and including a hopper to receive material from the belt, and a belt to pick up the material from the hopper and carry the same lengthwise to the loading car.

2. In a snow remover, a track traveling platform, a belt arranged for travel lengthwise the platform, means carried by the platform for driving the belt, a series of carriers arranged on the belt, and vertically arranged shields carried by and arranged in advance of the platform and having a vertical length exceeding the operative vertical sweep of the belt.

3. In a snow remover, a track traveling platform, a belt arranged for travel lengthwise the platform, means carried by the platform for driving the belt, a series of carriers arranged on the belt, and vertically arranged shields carried by and arranged in advance of the platform, and having a vertical length exceeding the operative vertical sweep of

the belt, said shields being disposed beyond the respective sides of the belt. 10

In testimony whereof I affix my signature.

FRANK J. BORRES.
